UNITED STATES PATENT OFFICE.

EDWARD P. SHELDON, OF BROOKLYN, NEW YORK, ASSIGNOR, BY MESNE ASSIGNMENTS, TO R. HOE AND CO., INC., OF NEW YORK, N. Y., A CORPORATION OF NEW YORK.

PLATE-PRINTING MACHINE.

Application filed August 25, 1923. Serial No. 659,288.

This invention relates to certain improvements in power plate printing machines.

It is the especial object of the invention to provide a small power plate machine suitable for printing bank notes and the like, in which a single plate is employed and in which there is provided a bed for the plate which is given a reciprocating motion past the inking, wiping, and impression members, and the movement of which is such that the support is momentarily stopped so that the plate may be polished by the operator before impression.

A further object of the invention is to provide a power plate machine which will print on both thin material, such as a sheet of paper, or on a relatively thick material, such as cardboard and the like, and to provide an impression mechanism which, when thin material is to be printed, will act to seize and carry the sheet during the impression and deliver the printed sheet, or where thick material is to be printed, will act to feed the material between the impression cylinder and the plate, the plate carrying the printed material away for manual delivery at the end of the machine.

It is a further object of the invention to provide means for heating the plate support and the plate during the travel of the plate through the machine so that the ink may be maintained at any desired working fluidity.

It is a further object of the invention to provide an improved mechanism for tripping the impression cylinder, of such character that the cylinder may be tripped off impression from different points in the machine.

With these and other objects not specifically referred to, the invention consists in certain novel parts, arrangements and combinations, which will be described in connection with the accompanying drawings, and the novel features pointed out in the claims hereunto annexed.

Referring now to these drawings—

Figure 1 is a diagrammatic side elevation, partly broken away and partly in section, of a power plate printing machine embodying the features of the invention.

Figure 2 is an enlarged side view, partly in section and partly broken away, of the

sheet feeding end of the machine shown in Fig. 1.

Figure 3 is a plan view of part of the construction shown in Fig. 2, the view being taken in the direction of arrow 3 of Fig. 2.

Figure 4 is an end elevation looking in the direction of the arrow 4 of Fig. 2.

Figure 5 is a plan view, partly broken away and partly in section, of the plate carrying bed and its associated parts.

Figure 6 is a partial sectional side view looking in the direction of arrow 6 of Fig. 5.

Figure 7 is a side view, partly in section, on an enlarged scale of the impression cylinder, feed board, and co-operating parts.

Figure 8 is a partial side view of the construction shown in Fig. 7, illustrating another position of the parts.

Figure 9 is an end view, partly broken away and partly in section of the construction shown in Fig. 7, the view being taken in the direction of arrow 9 of that figure.

Referring now to these drawings, 1, 2 indicate suitable side frames rising from a base 3 in which the various parts of the mechanism are positioned. In the particular construction illustrated, the power plate machine embodying the invention includes a single plate support 4 which is given a reciprocating motion back and forth in the machine, beneath an impression cylinder 5, its co-operating abutment 6, wiping mechanism 7 and 8, and an inking mechanism 9, the plate indicated at P being inked and wiped and then brought to one extreme end of the machine where it is gradually slowed down momentarily stopping to permit polishing after which the impression is effected.

Referring first to the bed supporting driving mechanism, in constructions embodying the invention in its best form, the driving mechanism will be of such character as to reciprocate the bed back and forth under the various agencies with which it co-operates with an easy even movement, and in which the bed at extremes of its movement will gradually slow down and momentarily stop so that the plate may be polished. In the particular construction illustrated, the bed is in the form of a frame which slides in channel guides 10, 11, supported from the side frames 1, 2, before referred to, these being best shown in Fig. 4. The bed central-

ly of its width is provided with a hanger block 12 from which depend hangers 13, these hangers being spaced to form a recess or way 14, the inside edges of these arms 13 being formed with guides 15.

Mounted to work in these guides is a travelling block 16, this block being pivotally mounted on a driving chain 17, this driving chain passing over sprockets 18 and 19 at opposite ends of the machine, the chain also passing over, if desired, adjusting sprockets 20, 21 mounted in brackets 22 suitably secured to the frame.

It will be observed that with this construction the block rides up and down in the hanger arms as the chain passes over the sprockets and this movement is such as to gradually slow down the movement of the bed and to stop the bed momentarily when the block is at midway position in passing over the sprocket, this position being shown in Fig. 2. With this construction, therefore, an easy regular driving movement is given the bed and the operator has a chance to polish the plate when it is in its extreme left hand position, considering Fig. 2.

Machines constructed in accordance with the invention will be capacitated to print on relatively thin material, such as a sheet of paper, or if desired on comparatively thick material such as cardboard. In the particular construction illustrated, where thin material is to be printed upon, this material is controlled by the impression cylinder during the printing operation and is delivered by this cylinder. Where a thick material as cardboard is to be printed on, however, the sheet of such material is printed by the impression cylinder, the sheet then remaining on the plate and being removed therefrom after the plate has reached the end of the machine opposite the feeding end. The specific construction for feeding a relatively light sheet, as paper, will be first described.

Referring to Figs. 2, 7, 8 and 9, the shaft 23 of the impression cylinder 5, which may be a blanketed cylinder, such blanket being indicated at 24, is mounted in bearings 25 supported to slide in guides 26 formed in upwardly extending portions 27 of side frames 28 rising from the base 3, before referred to. This cylinder is provided with sheet taking devices in the form of grippers 29 carried on a gripper shaft 30 suitably mounted in the heads 31, 32 of the cylinder.

This gripper shaft is rocked to open the grippers at the sheet taking point and at the sheet delivery point by means of a tumbler block 33 having a groove 34 in which take the ends of pins 35, 35', this tumbler block being fast on the shaft. The shaft is rocked against a spring rod construction 65 which normally holds the grippers closed.

While this spring rod construction may be of various characters, in the particular construction illustrated, on account of the small size of the gripper cylinder the spring rod construction has been adopted by which sufficient spring action can be obtained within the circumscribed cylinder limits. As shown, the shaft 30 is provided with an arm 36 to which is secured one end of a rod 37 provided with a spring 38. The other end 75 of this rod 37 engages with one end of a lever arm 39 pivoted at 40 in the cylinder head, the other end of this lever arm engaging a second rod 41 provided with a spring 42, the other end of this arm being secured at 43 in the cylinder head. With this construction a strong closing movement is imparted to the grippers.

The grippers 29 are opened by the pin 35 to take the head of the sheet so that it is forwarded in proper relation with the printing plate P, this position being shown in Fig. 7, and are operated by the pin 35' to open and release the sheet at the delivery point, the parts in this position being shown in Fig. 8.

The sheet is thus held in the control of the cylinder during the printing operation and is delivered by the cylinder. In the best constructions means are provided by which the end of the sheet will be lifted from the cylinder after it is released by the grippers and, furthermore, in the best constructions stripping devices will be provided co-operating with the lifters whereby the sheet is stripped from the cylinder as the cylinder rotates. While these desired objects may be effected in different ways, in the particular construction illustrated the cylinder is provided with a pair of lifting fingers 44 mounted on a rock shaft 45 suitably journaled in the heads of the cylinder. This shaft at one end beyond the head is provided with a hub 46 having an arm 47 carrying a stud 48 on which is secured a cam roll 49. This cam roll is adapted to ride on a cam 50 secured to one of the side frames before referred to, as clearly shown in Fig. 9, the cam riding over the face of this plate rocking the shaft and swinging the lifter fingers to lift the end of the sheet above the surface of the cylinder. Located adjacent the cylinder are strippers in the form of plates or frames 51 having bevelled ends 52 and sheet receiving surfaces 53. As the cylinder rotates the sheet is lifted off the lifters so that the ends project over the stripper plate and on the continued rotation of the cylinder the sheet is stripped or lifted therefrom, and the latter readily removed by the operator.

The tumbler pins 35, 35' are normally held out of engagement with the tumbler block, being moved into engagement by any suitable mechanism which may be varied.

In the particular construction illustrated these pins are mounted (see Figs. 7 and 9) to slide in brackets 55 secured to the frame of the machine, being normally moved 5 toward the left in Fig. 9 by means of springs 56, the shanks of the pins being reduced, as indicated at 57, to form a shoulder against which one end of the spring abuts, and the other end of the spring taking against one 10 of the supporting brackets. At their outer ends these pins are provided with adjustable abutments in the form of adjusting nuts 58 against which bear forked arms 59, 60, one of these arms being provided for each pin. 15 These arms are fast on rocking studs 61 secured in brackets 62 suitably secured to the frame of the machine. These arms are preferably mounted so as to be moved together, and in the particular construction shown, 20 there is provided arms 63, 64 carried on studs, these arms being connected by a link 65. These arms are manipulated to withdraw the pins from the path of the tumbler block at suitable times by means of a sleeve 25 cam 66 which operates the cam arm 67, thereby causing the yoke arm 59 to move the blocks to the right in Fig. 9 and withdraw the pins against the action of the springs 56.

The sleeve cam 66 is operated from any 30 suitable part of the machine, as from a rod 68 which, through mechanism hereinafter referred to, acts to throw the impression cylinder on and off impression. This sleeve cam 66 is locked in position on the rod by a 35 set screw 69. When it is desired for purposes hereinafter referred to, for the pins to be continuously held out of the path of the tumbler block for any desired time, this 40 may be effected by loosening the locking nut 69, sliding the sleeve cam upwardly on the rod so that the cam arm 67 is prevented 45 from moving downwardly. The parts will thus be held in such position, the sleeve cam being again locked in its adjusted position, with the pins permanently held out of 50 the path of the tumbler block.

The sheets are or may be fed to the press on an inclined feedboard 70 supported on brackets or standards 71 on the side frames 55 of the machine, the sheets being fed down this part by hand or in any other suitable way against a stop finger 72 which acts to 60 properly position the sheets so that they may be taken by the grippers. Where the sheets are thus fed against the stop finger means will be employed for withdrawing the finger or stop out of the way of the grippers so that the latter can seize the sheets. The 65 particular construction for effecting this may be somewhat varied, but in the particular construction illustrated the stop fingers are carried on blocks 73 fast on the rock shaft 74 suitably journaled in the brackets or standards 71, before referred to. This 70 rock shaft has secured thereto at one side a

rocking plate 75 (see Fig. 2) to one side of which is secured a spring rod construction 76. The other side of this plate has connected thereto a link 77 which is connected at its other end to one end of a lever arm 78 pivoted on a stud 80 (see Fig. 7) the other end of this lever arm carrying a cam roll 81. This cam roll is arranged to contact with a bar cam 82 removably secured as by screws 83 to the side of the plate support 4, before referred to. The stop fingers are thus normally held in up position by the spring 76 and are moved downwardly through the roll 81 running on the operating face of the bar cam, this operating face 80 projecting forwardly beyond the bed, as shown in Figs. 2 and 7, so that the stop finger is dropped at the proper time to enable the grippers to take the sheet from the board. If desired guide fingers, indicated 85 at 84 in Fig. 7, may be provided, these fingers extending above and forwardly of the feed board so as to space the leading end of the sheet from the cylinder and thus ensuring the grippers taking the sheet. 90

With this construction as so far described, the sheet is taken by the grippers as the bed comes into printing relation with the impression cylinder and is carried forward and around the impression cylinder and 95 delivered from the top side thereof. If desired margin rollers, indicated in Figs. 2 and 7 by the numeral 85, may be provided for controlling the sheet. In the printing operation the impression cylinder 5 will be 100 automatically thrown into printing relation with the plate and held there during the printing operation and then removed from printing engagement with the plate so that the plate can be carried freely beneath it 105 after it has been inked and wiped for the hand polishing. While this may be effected in various ways, in the particular construction illustrated the bearings 25 for the cylinder shaft have (see particularly Figs. 1, 110 2 and 4) pivoted thereto at each side of the machine at 86 arms 87. These arms are split arms connected by a screw bolt 88 having adjusting collars 89. The upper end of the arms 87 are pivoted at 90 to short 115 arms 91 on a rock shaft 92 taking in bearings 93 suitably formed in the side frames, before referred to.

At one side of the machine there is provided an operating arm 94 (see Fig. 2) the other end of this arm being connected at 95 to the upper end of the rod 68, before referred to. By making or breaking the toggle thus formed the cylinder is thrown into printing relation with the plate and removed 120 therefrom after the printing operation.

The operation of the rod 68 by which this is effected is or may be automatic. In the particular construction illustrated, the lower end of this rod is secured to an arm 96 of a 130

- lever 97 pivoted at 98 on a second lever 99. The other arm 100 of the lever 97 is secured to one end of an operating rod 101, the other end of this operating rod being controlled by a cam indicated at 102 in Fig. 1, this cam 102 being driven through connections hereinafter referred to. This cam acts to move the rod 101 to the left, as shown in Fig. 2, this movement causing a making of the toggle and throwing the cylinder on the impression against a spring 103, this spring acting to break the toggle when the rod 101 is freed by the cam to allow it to move to the right in Fig. 2.

Means are provided for locking the pivot point 98 of the operating lever 97 so that the rod 101 can effect its toggle making and breaking function, and means for breaking this lock so that if desired the movement of the rod 101 will not make the toggle, so that the cylinder can be left off impression when desired. In the particular construction illustrated, the lever 99 is pivoted at 104 in a bracket 105 suitably secured to the frame of the machine. This lever has an arm 106 to which is connected a spring rod construction 107. The lever is also provided with a latching arm 108 provided with a notch 109 and the lever is provided with a foot treadle 110. Co-operating with the locking arm of the lever is a latch 111 on the cross shaft 112, this shaft being provided at each side of the machine with operating pedads 113. Connected with the latch is a rod 114 which, at its other end is secured to a lever arm 115 pivoted on a shaft 116, this shaft being provided with operating treadles 117 at each side of the machine. The lever arm 115 is connected to the spring rod construction 118.

out of operative position, to the end of the machine where it may be lifted from the plate by an attendant before the return movement of the plate under the inking and wiping mechanisms, the temporary stoppage of the plate support at the end of the machine as heretofore described, giving time enough to permit this to be done. In the particular construction illustrated, this is effected by lifting the sleeve cam 66, before referred to, so that the gripper mechanism is rendered inoperative irrespective of the action of the toggle operating rod 68, and by removal of the bar cam 82 the spring 76 will render the stop finger 72 inoperative. Where such heavy material is to be fed a removable back stop 120 is provided on the feedboard 70, this stop being adjustable to provide for predetermined sheet lengths, this stop being arranged on the feedboard so that the sheet 85 when placed in position on the board against the stop will be positioned to be nipped between the cylinder and the plate and forwarded through for printing.

In machines embodying the invention in 90 its best form, means will be provided for heating the plate support and plate so as to keep the ink in the desired condition of fluidity, and in the best form of the invention this heating means will be electrical. While 95 various devices may be employed for this purpose, a convenient one is that shown in detail in Figs. 4, 5 and 6. As there shown, there is provided an electrical circuit including a pair of conductor rails 121, 122 in circuit with a line indicated by *a b* through which current is delivered from any suitable source of electrical supply, not illustrated. The bed is provided with heating elements in the form of a pair of conductor bars 123, 124 which are fed with current from

With this construction, when the parts are in the position shown in Fig. 2 with the foot treadle pressed down against the spring 107 the parts are in latched position and provide an abutment against which the rod 101 may work to operate the toggle actuating rod 68 to effect the making and breaking of the toggle. If, however, either of the levers 117 or 113 are depressed the latch 111 is removed from the notch 109 whereupon the movement of the rod 101 will cause the lever 99 to rock on the pivot 104 and the toggle will remain broken until the parts are returned to the position shown in Fig. 2.

As before stated it is very often desirable in this type of machine to print on a thick sheet, such as cardboard or other similar material too heavy to be handled by the impression cylinder, and the present machine is capacitated to do this. When such heavy material is to be printed, the sheet after it has been printed remains on the plate and passes with the plate under the wiping and inking mechanisms, which have been lifted

out of operative position, to the end of the machine where it may be lifted from the plate by an attendant before the return movement of the plate under the inking and wiping mechanisms, the temporary stoppage 70 of the plate support at the end of the machine as heretofore described, giving time enough to permit this to be done. In the particular construction illustrated, this is effected by lifting the sleeve cam 66, before 75 referred to, so that the gripper mechanism is rendered inoperative irrespective of the action of the toggle operating rod 68, and by removal of the bar cam 82 the spring 76 will render the stop finger 72 inoperative. Where 80 such heavy material is to be fed a removable back stop 120 is provided on the feedboard 70, this stop being adjustable to provide for predetermined sheet lengths, this stop being 85 arranged on the feedboard so that the sheet when placed in position on the board against the stop will be positioned to be nipped between the cylinder and the plate and forwarded through for printing.

In machines embodying the invention in its best form, means will be provided for heating the plate support and plate so as to keep the ink in the desired condition of fluidity, and in the best form of the invention this heating means will be electrical. While various devices may be employed for this purpose, a convenient one is that shown in detail in Figs. 4, 5 and 6. As there shown, there is provided an electrical circuit including a pair of conductor rails 121, 122 in circuit with a line indicated by *a b* through which current is delivered from any suitable source of electrical supply, not illustrated. The bed is provided with heating elements in the form of a pair of conductor bars 123, 124, which are supplied with current from a pair of shoes 125, 126 through circuits 127, 128. These conductor rails are dimensioned to transmit the required degree of heat to the bed to keep the ink in the desired fluid condition.

The mechanism is or may be driven from a suitable source of power, as a motor 129, which through a belt 130 drives the main driving shaft 131. From the shaft 131 through a train of gears 132, 133, 134, 135, 136, is driven a gear 137 on a shaft 138 extending lengthwise of the machine. This shaft 138 has at each end a gear 139 by which the carrier chain sprockets 18, 19, before referred to, are driven through a gear 140 on the sprocket shafts 141. Impression cylinder 5 is driven from the gear 136 through an intermediate 142 and a gear 143 on the impression cylinder shaft. The cam shaft 102, before referred to, is driven from the shaft 131 through a gear 144 on a shaft 145 having a worm 146, as indicated in dotted lines in Fig. 1.

The inking mechanism is driven from the

gear 139 through a gear 147 on the shaft 148 of the sprocket 19 through a train of gears 149, 150, 151.

The wiping mechanism is driven from the 5 shaft 131 through gears 152, 153 and intermediates 154, 155. This driving mechanism is shown only diagrammatically, as it is not necessary for an understanding of the present invention, and any suitable or desirable 10 driving arrangement, other than that indicated may be used as desired.

With the construction shown and described a plate printing machine has been produced 15 capacitated to handle either light or heavy 20 sheets without any rearrangement of the press, and a machine which may be continuously operated but which at the same time will give an opportunity for the hand polishing of the plate at one end of the plate 25 and delivery of the heavy products of the plate from the other end of the machine.

While the specific mechanisms shown and described are those preferred, it will be understood that various changes may be made 25 in certain mechanisms without departing from the invention as defined in the appended claims.

What I claim is:

1. In a plate printing machine, the combination of a travelling plate support, a co-operating impression cylinder, and means whereby a product may be delivered by the impression cylinder after printing or remain 30 on the plate and be delivered therefrom after the plate has passed the impression cylinder.

2. In a plate printing machine, the combination of a travelling plate support, a co-operating impression cylinder, means for tripping the cylinder on and off impression, 40 sheet taking devices on the cylinder, and means for preventing the action of the sheet taking devices without stopping the operation of the tripping means.

3. In a plate printing machine, the combination of a travelling plate support, a co-operating impression cylinder, means for tripping the cylinder on and off impression, and means whereby a product may be delivered by the impression cylinder after printing 45 or remain on the plate and be delivered therefrom after the plate has passed the impression cylinder.

4. In a plate printing machine, the combination of a travelling plate support, a co-operating impression cylinder, means for tripping the cylinder on and off impression, sheet taking devices on the cylinder which control the sheet during printing and from which the sheet is delivered after printing, 55 and means for silencing the operation of the sheet taking devices without stopping the operation of the tripping means.

5. In a plate printing machine, the combination of a travelling plate support, a co-operating impression cylinder, means where- 60

tripping the cylinder on and off impression, sheet taking devices on the cylinder, and connections from the tripping means for operating the sheet taking devices without effecting the operation of the tripping means. 70

6. In a plate printing machine, the combination of a travelling plate support, a co-operating impression cylinder, means for tripping the cylinder on and off impression, grippers on the cylinder, connections from 75 the tripping means for operating the sheet taking devices, and means for preventing the action of the sheet taking devices without stopping the operation of the tripping means. 80

7. In a plate printing machine, the combination of a travelling plate support, a co-operating impression cylinder, a toggle for tripping the cylinder on and off impression, a rod for operating the toggle, grippers on 85 the cylinder, connections from the rod for operating the grippers and means for preventing the operation of the connections without interfering with the operation of the rod. 90

8. In a plate printing machine, the combination of a travelling plate support, a co-operating impression cylinder, a toggle for tripping the cylinder on and off impression, a rod for operating the toggle, grippers on 95 the cylinder, a sleeve cam on the rod, and connections to the grippers operated by the cam.

9. In a plate printing machine, the combination of a plate support, a co-operating impression cylinder, means for tripping the cylinder on and off impression, grippers on 100 the cylinder, and connections from the tripping means for operating the grippers without effecting the operation of the tripping means. 105

10. In a printing machine, the combination of a printing member, a co-operating impression cylinder, means for tripping the cylinder on and off impression, grippers carried by the cylinder, connections from the tripping means for operating the grippers, and means for preventing the operation of the grippers without interfering with the operation of the tripping means. 110

11. In a plate printing machine, the combination of a plate support, a co-operating impression cylinder and inking, wiping and polishing mechanism, means for reciprocating the support past these devices, means 120 whereby a product may be delivered by the impression cylinder after printing or remain on the plate for delivery therefrom, and means for causing a dwell of the support beyond the impression cylinder and inking 125 mechanism.

12. In a plate printing machine, the combination of a travelling plate support, a co-operating impression cylinder, means where- 130

pression cylinder after printing or remain on the plate for delivery therefrom, and means for heating the support and plate.

13. In a plate printing machine, the combination of a travelling plate support, a co-operating impression cylinder, means whereby a product may be delivered by the impression cylinder after printing or remain on the plate for delivery therefrom, means for heating the support and plate, and means for causing a dwell of the support at different points in its path.

14. In a plate printing machine, the combination of a travelling plate support, a co-operating impression cylinder, means operable from different points of the machine for tripping the cylinder on and off impression, sheet taking devices on the cylinder, connections from the tripping means for operating the sheet taking devices, and means for preventing the action of the sheet taking devices without stopping the operation of the tripping means.

delivered by the impression cylinder after printing or remain on the plate and be delivered therefrom after the plate has passed the impression cylinder.

15. In a plate printing machine, the combination of a travelling plate support, a co-operating impression cylinder, means operable from different points of the machine for tripping the cylinder on and off impression, sheet taking devices on the cylinder, connections from the tripping means for operating the sheet taking devices, and means for preventing the action of the sheet taking devices without stopping the operation of the tripping means.

In testimony whereof, I have hereunto set my hand.

EDWARD P. SHELDON.
